Attorney

UNITED STATES PATENT OFFICE.

GID H. BREWER, OF WITTS SPRINGS, ARKANSAS.

REIN GUIDE.

Application filed January 8, 1924. Serial No. 685,008.

To all whom it may concern:

Be it known that I, Gid H. BREWER, a citizen of the United States, residing at Witts Springs, in the county of Searcy, 5 State of Arkansas, have invented a new and useful Rein Guide; and I do hereby declare the following to be a full, clear, and exact description of the invention, such as will enable others skilled in the art to which it 10 appertains to make and use the same.

The invention relates to rein guides for use on harness, preferably on the hames, and has for its object to provide a device of this character for guiding a check rein or 15 the driving reins in a manner whereby the rein will easily move and will be guided between rollers, thereby preventing wear on the rein.

A further object is to form the guide 20 from a U-shaped member having its arms vertically disposed and a member hingedly connected to the upper end of one of the arms and detachably connected to the other arm. Also to provide oppositely disposed 25 rollers for engaging the opposite sides of a rein and guiding the same during the movement of the rein between the rollers.

A further object is to mount the lower 30 roller on a transversely disposed shaft, and the vertically disposed rollers on L-shaped members, the lower ends of which are provided with eyes through which the lower 35 shaft extends, and the upper ends with angularly disposed arms extending into the arms of the U-shaped member.

A further object is to provide the hinged member with spaced arms, between which arms a roller is rotatably mounted for engaging the side of the rein.

With the above and other objects in view 40 the invention resides in the combination and arrangement of parts as hereinafter set forth, shown in the drawing, described and claimed, it being understood that changes 45 in the precise embodiment of the invention may be made within the scope of what is claimed without departing from the spirit of the invention.

In the drawing:—

Figure 1 is a front elevation of the guide 50 showing the same applied to a hame.

Figure 2 is a vertical transverse sectional view taken on line 2—2 of Figure 1.

Figure 3 is a horizontal sectional view 55 taken on line 3—3 of Figure 1.

Referring to the drawing, the numeral 1

designates a portion of a conventional form of hame, and 2 the U-shaped frame of the rein guide, which frame 2 is hingedly secured to the hame 1 by the eyes 3 carried by the frame and the eyes 4 carried by the hame. The U-shaped member 2 has its arms 5 in parallel relation to each other and hingedly connected at 6 to the upper end of one of the arms 5 is a bar 7, which bar is provided with a spring catch 8 adapted to spring over the shoulder 9 of the outer arm 5 for holding the bar 7 rigid. Bar 7 when in open position as shown in dotted lines in Figure 1 allows the rein 10 to be positioned between the rollers 11, where it will be guided in a manner whereby the rein 10 will not be worn on the sides thereof, for the reason that during the movement of the rein 10 it engages the 70 rollers 11 which have a rolling contact with the ring, consequently friction is prevented.

Rollers 11 are rotatably mounted on vertically disposed shafts 12, the lower ends of which are provided with eyes 13, and through the eyes the horizontally disposed shaft 14 extends which supports the roller 15, which engages the lower edge of the rein 10. Shaft 14 extends entirely through the arms 5 of the U-shaped member 2, and not only forms a shaft on which the roller 15 rotates, but also forms supporting means for the lower ends of the shafts 12. The upper ends of the shafts 12 terminate in horizontally disposed arms 16, which arms are imbedded in the arms 5 of the U-shaped member 2, and rigidly support the shafts 12 and the rollers 11 in positions where they will engage the sides of the rein 10 during lateral movement of the rein.

Rotatably mounted between the arms 17 of the hinged member 7 on a shaft 18 is a horizontally disposed roller 19, which roller is adapted to be engaged by the upper edge of the rein 10 upon an upward movement thereof for preventing wear or damage to the upper edge of the rein as it moves back and forth through the device. The arms 17 form means for preventing axial displacement or movement of the roller 19 and at the same time engage the inner sides of the arms 5 of the U-shaped member and prevent inward bending thereof when the device is open.

From the above it will be seen that a 110 rein guide is provided, wherein roller bearings will engage the opposite sides and edges

of the rein, thereby preventing wearing of the rein incident to movement, and the rein may be easily and quickly placed in the guide. Although the device has been described in connection with a rein or check rein, it is to be understood that the device may be used in connection with any movable piece of harness.

The invention having been set forth what 10 is claimed as new and useful is:—

1. A rein guide comprising a **U**-shaped frame having its arms in parallel relation, a member pivoted to the end of one of said arms, a spring catch carried by the free 15 end of said member and cooperating with a recess in the end of the other arm, a horizontally disposed roller carried by said member, a shaft extending through the arms adjacent their inner ends, a roller rotatably 20 mounted on said shaft, and in parallel relation to the first mentioned roller, shafts in parallel relation to the arms, one of the arms of said shafts being provided with 25 arms through which the first mentioned shaft extends, the ends of the parallel

shafts terminating in outwardly extending arms extending angularly into the arms of the **U**-shaped member.

2. A rein guide comprising a **U**-shaped frame, a member hingedly connected to the outer end of one of the arms of the **U**-shaped frame, the free end of said member being provided with a spring catch cooperating with the end of the other arm of the **U**-shaped member, a roller carried by the pivoted member, a roller carried by the transverse portion of the **U**-shaped member in parallel relation to the first mentioned roller and rollers adjacent the inner sides 35 of the arms of the **U**-shaped member in 40 parallel relation to each other and spaced apart.

In testimony whereof I have signed my name to this specification in the presence of two subscribing witnesses.

GID H. BREWER.
